UNITED STATES PATENT OFFICE

116,851

DESIGN FOR A LAWN MOWER REEL

Marlowe H. Kluter, Richmond, Ind.

Application July 7, 1939, Serial No. 85,906

Term of patent 14 years

To all whom it may concern:

Be it known that I, Marlowe H. Kluter, a citizen of the United States of America, residing at Richmond, in the county of Wayne and State of Indiana, have invented a new, original, and ornamental Design for a Lawn Mower Reel, of which the following is a specification, reference being had to the accompanying drawing, forming part thereof.

Figs. 1, 2 and 3 are a perspective view, a plan view and an end elevation, respectively, of a lawn mower reel embodying the design.

I claim:

The ornamental design for a lawn mower reel, as shown.

MARLOWE H. KLUTER.
